UNITED STATES PATENT OFFICE

97,352

DESIGN FOR A FLATIRON

John Koehl, Itasca, Ill.

Application March 8, 1935, Serial No. 55,791

Term of patent 3½ years

To all whom it may concern:

Be it known that I, John Koehl, a citizen of the United States, residing at Itasca, Du Page County, Illinois, have invented a new, original, and ornamental Design for a Flatiron, of which the following is a specification, reference being had to the accompanying drawing forming a part thereof.

The figure is a perspective view of the flatiron showing the new design.

I claim:

The ornamental design for a flatiron as shown.

JOHN KOEHL.
